(57) **CLAIM**

The ornamental design for a terminal metal fitting for conductive plate, as shown and described.

DESCRIPTION

FIG. 1 is a front, top and right side perspective view of a terminal metal fitting for conductive plate showing our new design;

FIG. 2 is a front view thereof, the rear view being a mirror image of the front view;

FIG. 3 is a top plan view thereof;

FIG. 4 is a bottom plan view thereof;

FIG. 5 is a right side view thereof; and,

FIG. 6 is a left side view thereof.

The broken lines illustrate portions of the terminal metal fitting for conductive plate that form no part of the claimed design. The dash-dotted lines denote the boundary of the claim and form no part of the claimed design.
